UNITED STATES PATENT OFFICE.

MILFRED L. GREENSTREET, OF MAPLEWOOD, MISSOURI, AND FREDERICK G. ROEDELL, OF DUBUQUE, IOWA, ASSIGNEES OF ONE-THIRD TO ARTHUR G. KENNEL, OF ST. LOUIS, MISSOURI.

GAME OR TOY.

1,402,596.

Specification of Letters Patent.

Patented Jan. 3, 1922.

Application filed November 20, 1920. Serial No. 425,308.

To all whom it may concern:

Be it known that we, MILFRED L. GREENSTREET, of Maplewood, St. Louis County, Missouri, and FREDERICK G. ROEDELL, of Dubuque, Iowa, citizens of the United States, have jointly invented a certain new and useful Improvement in Games or Toys, of which the following is a full, clear, and exact description, such as will enable others skilled in the art to which it appertains to make and use the same, reference being had to the accompanying drawings, forming part of this specification, in which,—

Figure 1 is a detail view of our game or toy.

Figure 2 is a detail view of one of the cardboard blanks from which the bed forming a part of the game or toy is made.

Figure 3 is an end elevational view of the bed blank partly folded.

Figure 4 is a detail sectional view of one of the tumbling objects employed in connection with the game or toy.

Figure 5 is a vertical sectional view through one end of a bed.

This invention relates to a new and useful improvement in games or toys, the object being to construct a device of the character described which is simple and cheap, and one which will prove interesting to adults as well as children.

While we have shown our improved game as comprising miniature twin beds arranged in a room or chamber in which there are two images, or tumbling objects, shaped to represent characteristic figures, it is obvious that these tumbling objects could be differently shaped, such as, for instance, to represent pigs, and instead of beds, the representation of a pen could be used; however, in the form of my invention shown, the object is to cause the two tumbling objects to jump into their respective beds and lie down. The tendency of these objects is to always keep an upright position occasioned by the weighted lower end, as indicated in Figure 4, wherein 1 indicates the object formed of celluloid, or other light material, in the base of which is arranged a drop of lead or solder, as indicated at 2. It is the purpose of this weighted end to cause the object to stand on end, as shown in Figure 1.

3 is the box or casing having its inner side walls and bottom preferably decorated with

colored paper to represent the wall paper and carpet of a room. The top of this box is in the form of a sheet of glass 4, which may be hinged or permanently secured in position.

5 indicates a bed blank preferably made by dies from a sheet of cardboard. This bed blank is scored or cut at its four corners, as indicated by the full lines 6, to form the head and foot boards 7 and 8, respectively. Tongues, 9 are formed by scoring the cardboard along the lines 10. The head and foot pieces are bent along dotted lines 11 so that they will stand perpendicular to the main portion of the bed, as shown in Figure 3. The side pieces are bent downward along the lines 12, as indicated by dotted lines in Figure 3, and the ends 13 of these sides pieces are then bent inwardly along the dotted lines 14 so that they will overlap the tongue portion 9, after which a staple or other fastening means 15 is passed through the portions 13 and 9 to secure them together, whereupon the bed can be placed in an upright position on the bottom of the box and held there by the use of some appropriate adhesive material.

In bending the tongues 9 away from the body portion of the bed, an opening 5^a is left near the head and foot boards, respectively, when the cover 16 of the bed, preferably formed of colored paper, is pasted in position over and around the bed, it may be depressed, as shown in Figure 5, to form a slight cavity.

In the form of our invention shown, there are twin beds, that is, two small beds in the same box and two tumbling objects, one for each bed, and by gradually working them down by holding the box at an angle so that they will rest against the head board or footboard of the beds, respectively, and preferably in the cavities located adjacent thereto, and then turning the box at a greater angle until the tumbling objects are standing upon the head boards or foot boards, and then slowly restoring the box to its normal horizontal position, the tumbling objects can be made to appear as lying down or reclining on the beds.

What we claim is:

1. A game or toy comprising a box having horizontally and vertically disposed adjacent walls representing an object, movable

objects weighted at one end only so that they will normally stand in an upright position, whereby when said box is tilted so that the weighted ends of said objects are 5 against a normally vertical wall, the restoration of said box to its horizontal position will cause said objects to lie down or occupy an abnormal position.

2. A game or toy employing a plurality of 10 tumbling objects and miniature representations of beds enclosed in a suitable box, said beds having covered depressions near their head boards.

3. A game or toy comprising a box with- 15 in which is immovably secured a miniature representation of a bed, said bed being formed from a blank which is cut or scored and bent so that its end portions overlap, there being fastening means for said over- 20 lapping end portions, and means for im-

movably securing the lower edges of said end portions to the bottom of the box.

4. A game or toy comprising a box for enclosing a miniature representation of a bed, said bed being formed from a single 25 blank of cardboard which is cut or scored to form head boards, foot boards and side pieces, the head boards and foot boards being bent perpendicularly to the main portion of the blank and the side members being bent down with their ends folded over, tongue portions extending from the head portions and foot portions, respectively, there being fastening devices for securing said bent ends to said tongues. 35

In testimony whereof we hereunto affix our signatures this 12th day of November, 1920.

MILFRED L. GREENSTREET.
FREDERICK G. ROEDELL.
